Patented Dec. 23, 1975

238,116

TWO PIECE BATHING SUIT

Barbara L. Firkser, 1066 McLean Ave.,
Wantagh, N.Y. 11793

Filed May 3, 1974, Ser. No. 466,799

Term of patent 3½ years

Int. Cl. D2—02

U.S. Cl. D2—41

FIG. 1.

FIG. 2.

FIG. 1 is a front perspective view of a two piece bathing suit embodying my new design; and

FIG. 2 is a rear elevational view thereof.

I claim:

The ornamental design for a two piece bathing suit, substantially as shown and described.
